A. C. GORDON,
AUXILIARY STEAM GENERATOR,
APPLICATION FILED FEB. 26, 1918.

1,318,376.

Patented Oct. 14, 1919.

UNITED STATES PATENT OFFICE.

AI C. GORDON, OF GLENS FALLS, NEW YORK.

AUXILIARY STEAM-GENERATOR.

1,318,376.

Specification of Letters Patent. Patented Oct. 14, 1919.

Application filed February 26, 1918. Serial No. 219,307.

To all whom it may concern:

Be it known that I, AI C. GORDON, citizen of the United States, residing at Glens Falls, in the county of Warren and State of New York, have invented certain new and useful Improvements in Auxiliary Steam-Generators, of which the following is a specification.

This invention relates to an improved auxiliary steam generator for ship power systems and has as its primary object to provide a device of this character adapted to utilize the waste heat from the ship's boilers for generating steam which may be used along with the steam from the boilers for propelling the ship or for any other purpose desired.

The invention has as a further object to provide a device of the above described character adapted to be interposed in one of the smoke flues of the ship's boilers and provided with a water jacket so that the heat passing through the flue and through the device will be utilized for heating the water within the said jacket to generate steam therefrom.

The invention has as a still further object to provide a device of the above described character which will be formed in sections or units so that the size of the device may be varied to suit the conditions of different ships by simply increasing or decreasing the number of sections or units employed.

And the invention has as a still further object to provide an improved arrangement for connecting the sections of the device so that the water contained thereby may have free circulation from one section to the other.

Other and incidental objects will appear as the description proceeds, and in the drawings wherein I have illustrated the preferred embodiment of the invention, and wherein similar reference characters designate corresponding parts throughout the several views:

Figure 1 is a fragmentary elevation showing my improved device in connection with a conventional type of ship's boiler, three of the decks of the ship being also conventionally shown in section.

Fig. 2 is a detail vertical sectional view showing the device attached and illustrating the manner in which the sections or units of the device are connected.

Fig. 3 is a transverse sectional view taken

through one of the sections of the device and showing the passages formed thereon for establishing communication between the sections, and

Fig. 4 is a detail perspective view, partly broken away, showing one of the sections detached.

In order that the construction, mounting and operation of my improved generator may be accurately understood, I have, in the drawings, shown the device in connection with a conventional type of ship's boiler 10 having a smoke flue 11 and steam dome 12. The first, second and third decks of the ship are also conventionally shown at 13. Coming now more particularly to the subject of the present invention, my improved device is formed with a body made up of a plurality of cylindrical sections or units and including terminal sections 14 and 15 respectively, between which are arranged a plurality of intermediate sections 16. The terminal sections 14 and 15 each include a cylindrical casing 17 surrounded by an annular water jacket 18 closed at its outer end by the wall of the jacket which extends across the outer end of the wall of the casing and is continued to provide a reduced extension or collar 19. Closing the jacket at its inner end is a flat end wall 20. Extending transversely through the casing 17 is a plurality of parallel circulating pipes 21 opening into the water jacket and provided at the lower sides thereof with flat upwardly diverging deflecting faces for directing heated currents through the casing toward the wall thereof for more effectually heating said wall. Formed on the water jacket preferably at quadrantly spaced points thereon is a plurality of radially extending tubular passages 22 which are vertically disposed. Preferably, these passages are of a radius corresponding to the width of the water jacket. Opening into one of the passages of the section 14 is an inlet 23 and communicating with one of the passages of the section 15 is an outlet 24.

The intermediate sections 16 of the generator, like the terminal sections, each include a cylindrical casing 25 surrounded by an annular water jacket 26 closed at its ends by flat end walls 27.

Extending transversely through the casing is a series of parallel circulating pipes 28 similar to the series of pipes 21 of the terminal sections. Formed on the water

jacket at quadrantly spaced points are a plurality of vertical tubular passages 29 corresponding to the passages 22 of the terminal sections. It will thus be clear that 5 the terminal and intermediate sections are, as shown in Fig. 2 of the drawings, adapted to mate end to end for forming the generator when the passages 22 and 29 of the sections will align vertically of the generator 10 body to provide passageways extending from end to end thereof. However, in this connection it should be noted that the said sections are so arranged one upon the other that the circulating pipes of one section are 15 disposed at right angles to the pipes of the preceding section. Formed at the inner ends of the passages 22 of the terminal sections 14 and 15 are oppositely directed lateral ears or lugs 30 and fitted through these lugs 20 to extend at opposite sides of each of the passageways are tie rods 31 detachably connecting the said sections. The sections are thus rigidly held together to provide a continuous smoke passage through the body 25 and, as shown in Fig. 1, the body is interposed in the smoke flue 11 of the boiler 10 to extend vertically above the boiler with the reduced extension 19 of the section 14 of the generator body receiving one end of the flue 30 while the opposite end of the flue is fitted over the reduced extension 19 of the section 15. Thus, the waste products of combustion from the boiler will flow through 35 the generator. In Fig. 1, I have shown the generator of a length to extend upwardly through the first and second decks of the ship. However, as will be clear in view of the preceding description, the length of the generator may be readily varied to suit the 40 conditions of different ships or the requirements of different boilers by simply increasing or decreasing the number of sections employed in the body of the generator.

As will now be observed upon reference to 45 Fig. 2, the end walls 20 and 27 of the sections are, at the passages 22 and 29, formed with registering openings and detachably engaged within these openings are double ended coupling nipples 32 wedged at their 50 ends within the said openings and establishing communication between the passages, making the passageways continuous, vertically of the generator body. This construction provides a very convenient arrangement 55 whereby the passages of the sections may be readily connected and since the nipples are arranged to establish communication directly between the ends of the passages, the said passages will, by being enlarged radially with respect to the water jackets, provide free circulation between the water jackets of the sections. Connected with the inlet 23 of the section 14 is a pipe 33 communicating with which is a water 60 supply pipe 34 having a usual cut off valve 65

35 interposed therein. The pipe 33 is carried to a water tank 36 mounted on a level adjacent the upper extremity of the generator. Accordingly, this tank is, as shown in Fig. 1, arranged upon the second deck of 70 the ship and is preferably equipped with a sight tube 37. Controlling communication between the tank and the pipe 33 is a usual shut off valve 38 in the said pipe. Leading from the outlet 24 of the section 15 is a 75 steam line pipe 39 which is connected with the steam dome 12 and leading from the said dome in communication with the pipe 39 is a steam supply pipe 40 in which is preferably interposed a usual cut off valve 80 41. Leading from the pipe 39 to the tank 36 is a branch pipe 42 and preferably a usual cut off valve 43 is interposed in the pipe 39 between the generator and this branch pipe. In use, water is admitted through the pipe 85 34 to flow into the generator and into the tank 36, the level of the water in the generator being easily determined by means of the sight tube 37 upon the tank. In order to allow for the rolling of the ship, the tank 90 is preferably only partially filled with a corresponding partial filling of the generator, so that space may be allowed in the uppermost sections of the generator for rise and fall of the water therein with the movement 95 of the ship. As will, of course, be understood, the water will, when the generator is thus filled, flow into the circulating pipes 21 and 28 so that the waste products of combustion of the boiler 10 is passing through 100 the generator as previously described, will flow over these pipes and against the walls of the flue passage of the generator for heating the water therein. The steam thus generated will then be carried off through the 105 pipe 39 to the steam dome 12 where it will become mixed with the steam generated by the boiler and thus directed off through the pipe 40 to a point of use. I therefore provide an arrangement whereby a great portion 110 of the heat which would ordinarily be wasted through the smoke flue of the boiler will be utilized for generating a supply of steam auxiliary to the boiler supply and such auxiliary supply of steam may, of course, be used in connection with the boiler supply for propelling the ship or independently of such boiler supply for driving other machinery upon the ship.

Having thus described the invention, what 12 is claimed as new is:

1. An auxiliary steam generator including a body having a casing providing a continuous central smoke passage opening through the ends of the body, a water jacket surrounding the casing and uniformly spaced therefrom, the body being formed of independent detachably connected sections and the space between the jacket wall and the wall of the casing upon each of the sections 13

being uninterrupted, a water passageway formed on the walls of the jackets and open to the jackets, said passageway being enlarged to project outwardly from the jacket
5 walls and establishing communication between the jackets of the sections, and an inlet and outlet for said jackets.

2. In a device of the character described, the combination with a boiler including a flue, 10 of an auxiliary steam generator interposed between lengths of the flue to form a continuation thereof and having a water jacket, a water supply tank, circulating pipes leading

from the jacket at opposite ends of the generator and connected with opposite ends of 15 the tank, a pipe forming an extension of one of said first mentioned pipes and having direct connection with the boiler for carrying off steam from the jacket, and valves interposed in said circulating pipes whereby 20 said valves may be closed to cut off communication between the tank and jacket and the generator displaced from the flue.

In testimony whereof, I affix my signature.

AI C. GORDON. [L. s.]
